[57] CLAIM

The ornamental design for an aerodynamic vehicle fairing, as shown and described.

DESCRIPTION

FIG. 1 is a perspective view of the aerodynamic vehicle fairing showing my design;

FIG. 2 is a side elevational view thereof;

FIG. 3 is a top view thereof;

FIG. 4 is a bottom view thereof;

FIG. 5 is a front view; and,

FIG. 6 is a rear view of the aerodynamic vehicle fairing showing my design.

FIG. 1

FIG. 2

FIG. 3

FIG. 4

FIG. 5

FIG. 6
